C. P. ABBOTT

SANITARY HANDLE, KNOB, AND THE LIKE

Filed Aug. 4, 1922

Invention:
Charles P. Abbott
and Clyde L. Rogers
his assignee

UNITED STATES PATENT OFFICE.

CHARLES P. ABBOTT, OF ALLSTON, MASSACHUSETTS.

SANITARY HANDLE, KNOB, AND THE LIKE.

Application filed August 4, 1922. Serial No. 579,859.

To all whom it may concern:

Be it known that I, CHARLES P. ABBOTT, a citizen of the United States, and resident of Allston, Boston, county of Suffolk, Commonwealth of Massachusetts, have invented an Improvement in Sanitary Handles, Knobs, and the like, of which the following description, in connection with the accompanying drawings, is a specification, like characters on the drawings representing like parts in each of the several views.

This invention relates to knobs and handles equipped with provision for keeping the same at all times in a sterile and sanitary condition. While having other and more general fields of usefulness the invention is well adapted and designed for embodiment in knobs of doors and in pull handles, such as used with closet cisterns and the like. The invention comprises a knob, handle or the like equipped with provision for receiving and holding a quantity of substance preferably in crystals or more or less comminuted form, or other substance capable of giving off gradually and continuously for a long period an emanation, vapor, or mist capable of disinfecting and sterilizing the handle and its locality, such substance also preferably being distinguished by a pleasing odor capable of overcoming any unpleasant odor in the vicinity. The foregoing and other objects and advantages of the invention will more fully appear from the following detailed description taken in connection with the accompanying drawings, and the distinctive features of novelty will be pointed out in the appended claims.

Referring to the drawings:

Fig. 1 is an elevation of a pull handle embodying the invention, a portion thereof being broken away in section;

Fig. 2 is an end view thereof;

Fig. 3 is a transverse section on line 3—3 of Fig. 1;

Fig. 4 is an elevation of a door knob embodying the invention;

Fig. 5 is an elevation showing an outer portion of the knob of Fig. 4 viewed from the inner side thereof;

Fig. 6 is a longitudinal sectional view of the knob portion shown in Fig. 5;

Fig. 7 is an elevation from the inner side of the inner knob portion of the knob of Fig. 4;

Fig. 8 is a longitudinal section thereof;

Fig. 9 is a transverse section on line 9—10 of Figure 4 showing a locking device in locking position;

Fig. 10 is a similar section showing the locking device disengaged; and

Fig. 11 is an elevation showing a portion of a knob receiving shank adapted for use with the invention.

Referring first to Figures 1, 2 and 3, 10 indicates a pull handle which may be of a shape generally similar to that employed in pull handles for closet cisterns, being shown as having a ring 11 at its inner end to be engaged by a pull chain 12. In accordance with my invention, this pull handle is made as a hollow shell either of metal or other suitable material. Adjacent its outer end, this shell is formed or provided with an inwardly extending flange 13 and with a threaded collar or nipple 14 extending outward from the inner edge of such flange. The outer extremity of the handle is formed as a separate cap 15 of cup shape with a band 16 around its periphery rebated internally to provide a seat engaging the outer edge of the shell 10. This cap 15 is also provided with an inwardly extending collar 17 threaded to engage the threads of the collar 14. The cap 15 may be formed as a one piece cup, but as herein shown, I form it with a central opening 18 which has extending thereacross a foraminous sheet or mesh 19. The entire extent of the handle and body 10 and also of the cap 15 are perforated with a multiplicity of minute holes 20 therethrough. In the use of the invention, the cap 15 being removed, the handle is partly or wholly filled with a substance D either in the form of crystals, or more or less comminuted, or otherwise, adapted to give off slowly and gradually but continuously during a long period, an emanation or vapor that, passing outward through the minute holes 20 keeps the handle in a thoroughly sterile and sanitary condition, this substance being also preferably of a character to disseminate a pleasing odor in the locality. In Figures 4 et seq, I show an application of the invention to knobs for doors and the like. In this case the knob is made hollow and in two parts 21, 22 with both parts preferably perforated with minute holes therethrough throughout the area thereof. The outer knob portion 22 is formed with a peripheral rib rebated as indicated at 23 to fit

the inner side of the door or other surface to be secured.

Fig. 9 is a transverse section on line 9—10 of Figure 4 showing a locking device in locking position;

Fig. 10 is a similar section showing the locking device disengaged; and

Fig. 11 is an elevation showing a portion of a knob receiving shank adapted for use with the invention.

Referring first to Figures 1, 2 and 3, 10 indicates a pull handle which may be of a shape generally similar to that employed in pull handles for closet cisterns, being shown as having a ring 11 at its inner end to be engaged by a pull chain 12. In accordance with my invention, this pull handle is made as a hollow shell either of metal or other suitable material. Adjacent its outer end, this shell is formed or provided with an inwardly extending flange 13 and with a threaded collar or nipple 14 extending outward from the inner edge of such flange. The outer extremity of the handle is formed as a separate cap 15 of cup shape with a band 16 around its periphery rebated internally to provide a seat engaging the outer edge of the shell 10. This cap 15 is also provided with an inwardly extending collar 17 threaded to engage the threads of the collar 14. The cap 15 may be formed as a one piece cup, but as herein shown, I form it with a central opening 18 which has extending thereacross a foraminous sheet or mesh 19. The entire extent of the handle and body 10 and also of the cap 15 are perforated with a multiplicity of minute holes 20 therethrough. In the use of the invention, the cap 15 being removed, the handle is partly or wholly filled with a substance D either in the form of crystals, or more or less comminuted, or otherwise, adapted to give off slowly and gradually but continuously during a long period, an emanation or vapor that, passing outward through the minute holes 20 keeps the handle in a thoroughly sterile and sanitary condition, this substance being also preferably of a character to disseminate a pleasing odor in the locality. In Figures 4 et seq, I show an application of the invention to knobs for doors and the like. In this case the knob is made hollow and in two parts 21, 22 with both parts preferably perforated with minute holes therethrough throughout the area thereof. The outer knob portion 22 is formed with a peripheral rib rebated as indicated at 23 to fit

the inner side of the door or other surface to be secured.

Fig. 9 is a transverse section on line 9—10 of Figure 4 showing a locking device in locking position;

over the outer edge of the inner knob portion 21. Each of these knob portions has a web extending across the lower portion of the inner side thereof and upward somewhat 5 past the center, such web in the outer knob portion being indicated at 24 and that of the inner knob portion at 25, these webs thus lying side by side when the knob is assembled. The outer knob portion has a squared 10 socket sleeve 26 extending inwardly therefrom adapted to receive a squared knob shank 27, while the inner knob portion 21 has a shorter sleeve 28 extending inwardly therefrom with a squared socket receiving 15 the sleeve 26, this sleeve 28 being circular exteriorly. For holding the knob portions 21, 22 in assembled relation on the knob shank 27, a spring clasp 29 is provided to fit around the sleeve 28, this clasp bearing adjacent one end thereof a key 30 which is 20 adapted to extend through a slot 31 provided therefor in the sleeve 28, and a registering slot 32 in the sleeve 26 so that this key may engage one of a series of notches 33 in the 25 knob shank. These notches 33 are preferably rectangular so that the key 30 engaged therein is insured against casual dislodgment. The slot 31 in the sleeve 28 preferably has one side thereof rebated as indicated 30 at 31^a so as to permit the key 30 to ride outward thereon as the clasp 29 is turned, and the clasp 29 may have its extremity slightly turned outward as indicated at 29^a, so as to constitute a finger hold. In 35 use, one or both of the portions 21, 22 is partly filled with the disinfectant sterilizing substance D, and the webs 24, 25 constitute retaining walls to hold the substance in place in the two knob portions as they are assembled. Then the knob portions being brought 40 together may be instantly and easily secured

to the knob shank by means of the key 30 as described. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention. 45 50

Having described my invention, what I claim as new and desire to secure by Letters Patent is:

1. A sanitary knob or handle for doors or the like composed of two shell portions adapted to be assembled side by side, each thereof having a sleeve extending inwardly therefrom with the sleeve from the outer portion adapted to fit within the sleeve of the inner portion and to receive a knob shank, each of said portions having a multiplicity of relatively small holes therethrough, and means for locking said portions in assembled relation upon a knob shank. 55 60 65

2. A sanitary knob for doors or the like composed of two shell portions adapted to be assembled side by side, each thereof having a sleeve extending inwardly therefrom, with the sleeve from the outer portion adapted to fit within the sleeve of the inner portion and to receive a knob shank, each of said shell portions having a web extending across the lower portion of the inner side thereof and upward past the center, each of said portions having a multiplicity of relatively small holes therethrough, and means for fixing said portions in assembled relation upon a knob shank. 70 75

In testimony whereof, I have signed my name to this specification.

CHARLES P. ABBOTT.
